UNITED STATES PATENT OFFICE.

GEORGE A. PEACOCKE, OF VICTORIA, BRITISH COLUMBIA, CANADA.

GAME APPARATUS.

1,314,754.

Specification of Letters Patent.

Patented Sept. 2, 1919.

Application filed August 6, 1918. Serial No. 243,530.

To all whom it may concern:

Be it known that I, GEORGE AUGUSTUS PEACOCKE, a subject of the King of Great Britain, residing at Victoria, Province of 5 British Columbia, Dominion of Canada, have invented certain new and useful Improvements in Game Apparatus; and I do hereby declare the following to be a full, clear, and exact description of the invention, 10 such as will enable others skilled in the art to which it appertains to make and use the same.

My invention relates to improvements in game apparatus and more particularly to 15 such an apparatus adapted for use in connection with marble shooting.

An important object of this invention is to provide a game apparatus of the character described comprising in part, a pair 20 of foldable trays, one of said trays having a pair of openings therein normally closed by doors, the doors being adapted to be opened upon being struck by a marble.

A further object of the invention is to 25 provide a game apparatus of the character described, which is of highly simplified construction, cheap to manufacture, very compact and neat in appearance.

A further object of the invention is to 30 provide a game apparatus of the character described having means for amusing both young and old.

Other objects and advantages of the invention will be apparent during the course 35 of the following description.

In the accompanying drawings forming a part of this specification and in which like numerals are employed to designate like parts throughout the same,

40 Figure 1 is a perspective of a game apparatus embodied in my invention, showing the same in an operative position,

Fig. 2 is a horizontal section through the same,

45 Fig. 3 is a perspective of a door embodied in the invention,

Fig. 4 is a perspective of a shaft or pin upon which the door shown in Fig. 3 is mounted,

50 Fig. 5 is a front elevation of the game apparatus.

Fig. 6 is a central vertical longitudinal

section through the same, showing the apparatus in an open position,

Fig. 7 is a central vertical longitudinal 55 section through the apparatus, showing the same closed,

Fig. 8 is a central vertical longitudinal section through the apparatus, showing a slightly modified means for retaining the 60 apparatus open, and,

Fig. 9 is a perspective of one form of the means for retaining the apparatus open.

In the drawings wherein for the purpose of illustration is shown the preferred 65 embodiment of my invention, the numeral 10 generically designates the apparatus, which in manufacture may be of any suitable metal. The apparatus comprises in part a base 10' having side walls 11 and 70 a single front wall 12. Hingedly secured to the rear end of the base or tray 10' is a support generically designated by the numeral 13. The support or frame 13 is secured to the side walls 11 of the base 10' 75 by rivets 14. The rivets 14 extend through vertical side walls 15 of the frame 13. As clearly shown in Figs. 1 and 2, the frame 13 is provided with vertically disposed spaced partitions 16, thus forming a pair 80 of openings 17. The partitions 16 comprise spaced vertically disposed walls 18. Doors 19 are pivotally arranged within the openings 17. As clearly shown in Fig. 3, the doors 19 are provided in their lower 85 end portions with side flanges 20 extending parallel to the partitions 16. The flanges 20 are provided with alining apertures 21 adapted for the reception of a transversely extending pin 22. With reference to Fig. 90 1, it will be apparent that the doors 19 are adapted for a pivotal movement on the shaft 22. To retain the doors 19 in a normally closed position, transversely extending weighted strips 23 are secured along 95 their lower end portions.

As clearly shown in Fig. 7, the frame 13 when not in use, is adapted to be folded within the base 10'. To retain the frame 15 in an upright position, a brace 24 is 100 provided. As clearly shown in Fig. 9, the brace 24 is provided with a substantially U-shaped arm 25 in its forward end portion, said U-shaped arm 25 being adapted to ex-

tend over the forward side 12 of the base 10'. The rear end portion 26 of the brace 24 is adapted to engage the side walls 18 of the central partition 16 as clearly shown in Fig. 2.

5 In Fig. 8 is shown a slightly modified means for retaining the frame 15 in its upright position. A brace 27 is arranged in the casing 10 and has pivotal connection with the upright 15 as at 28. The lower end portion of the brace 27 is hooked and is adapted to engage the base 10' as at 29.

10 In the use of my improved game apparatus, it will be apparent that the object of the game is to shoot marbles through the openings 17. Upon the passage of the marbles through the openings 17, the same will be retained in the base 10 by virtue of the side walls 11 and 12. By reason of the 15 weighted portion 23 carried by the lower end portion of the door 19, the door will immediately seek a vertical position after being opened by the passage of the marble.

20 While I have shown and described the preferred embodiment of my invention, it is understood that I may make such minor changes in arrangement and construction of parts as will remain within the spirit of the invention and the scope of the appended 25 claims.

Having thus described my invention, what I claim is:

30 1. A game apparatus comprising, a base having vertical, front and side walls; a frame hinged to one end portion of the base and adapted to be folded therein, said frame having a plurality of longitudinally disposed openings therein; doors arranged

within said openings and horizontally pivoted to said frame at a point between 40 their ends; and means to support the frame in an upright position.

2. A game apparatus comprising, a base having vertical, front and side walls; a frame hinged to one end portion of the 45 base and adapted to be folded therein, said frame having a plurality of longitudinally extending openings in one side thereof; doors pivotally arranged within said openings, said doors being horizontally hinged 50 to said frame at a point intermediate their ends; means to retain the doors in a normally closed position; and means to support the frame in an upright position.

3. A game apparatus comprising, a base 55 having vertical, front and side walls; a frame hinged to one end portion of the base and adapted to be folded therein, a plurality of longitudinally extending spaced 60 parallel partitions disposed in said frame, thus forming a plurality of longitudinally extending openings; doors arranged within said openings; flanges carried by said doors along their longitudinal edges and disposed at right angles thereto; a pin extending horizontally through said frame and said flanges and adapted to function as a 65 hinge; means to retain said doors normally closed; and means to support said frame in an upright position.

70 In testimony whereof I affix my signature in presence of two witnesses.

GEORGE A. PEACOCKE.

Witnesses:

WILLIAM F. HAMILTON,
C. YULE.
